ELECTRIC TORCH LIGHTER

Clarence E. Cady, Omaha, Nebr.

Application August 11, 1938, Serial No. 224,356

4 Claims. (Cl. 219—32)

This invention relates to an improvement in a stationary tool or device to cause automatic ignition of torches used in electric welding.

The invention has for one of its objects to provide an inclined holder for the torch arranged to be moved vertically for disposing the torch at a specified inclination relative to the arc of ignition and relative to certain deflecting-plates for controlling ignition flashes. 5 Another object is to provide such a mounting for the movable electrode that its axis, during operation, will be maintained parallel with the axis of the stationary electrode.

The invention includes a pair of electrodes disposed in a vertical plane for avoiding undue friction and permitting uniform lubrication of the movable electrode.

Also the invention includes a vertically disposed plunger-bar movable by weight of the torch held thereby for causing ignition of the torch.

A further object has been to provide a housing for the several operating parts to protect the flash and ignition from the wind and to provide a single passageway for the outward movement of any excess products of combustion. 20

Also it has been an object to employ few and simple parts which will operate practically and accurately and may be conveniently manufactured at a moderate cost.

With the foregoing objects in view, the invention presents a new and useful construction, combination and arrangement of parts as described herein and claimed, and as illustrated in the accompanying drawing, it being understood that changes may be made in form, size, proportion of 35 parts and minor details, said changes being within the scope of the invention as claimed.

In the drawing, Fig. 1 is a sectional view on line 1—1 of Fig. 2, showing operating parts of the torch igniter. Fig. 2 is a view of the device 40 in vertical section on line 2—2 of Fig. 1, and Fig. 3 is a plan view of the device.

Referring now to the drawing for a particular description, I provide an upright casing or housing 4, preferably of rectangular form, having an opening 5 in its top and provided with a pair of parallel, inclined deflecting-plates at two opposed edges indicated at 6 and 7, said plates respectively projecting outwardly and inwardly of the casing as shown in the drawing.

50 Numeral 8 indicates a tubular guide which extends into the top of the casing, this guide being disposed in a vertical position.

Near the top of the casing is disposed a stationary electrode 9, said electrode being secured

to a stationary tubular support 10 and being electrically energized as shown in the drawing.

Numeral 11 indicates a movable electrically energized electrode provided with a tubular jacket or housing 12, said electrode being disposed below and in vertical alignment with the stationary electrode 9 and, together with the tubular housing 12 being adapted to have free sliding movements in a stationary sleeve 14, said sleeve being provided, longitudinally with a slot 15 opening 10 on the interior of the casing; and this sleeve 14 has a length sufficient to receive the free end portion of the electrode 7. Also the slot 15, preferably, extends to the upper end of said sleeve 14.

Numeral 16 indicates a spring suitably insulated and attached to the casing, said spring being secured to the tubular housing 12 of the movable electrode.

Any suitable electric conductors may be used for energizing the two electrodes, and no particular description is considered necessary, except to state that the resistant electric coil 17 wound upon the insulated core 18 has a projecting part 19 of spiral form attached to the tubular jacket 12, said part 19 being flexible and operating simply as an electrical conductor and not resisting the slidable movements of the electrode 11 in an appreciable degree.

Numeral 20 indicates a rock-bar mounted between its ends to have swinging movements on 30 a horizontal pivot-pin 21.

Numeral 22 indicates a vertically movable plunger-bar mounted in the tubular guide 8 and provided with an inclined concave cap 23 for supporting a torch 24.

The pivotal mounting of the plunger-bar upon one end of the rock-bar is indicated at 24, and the opposite end of the rock-bar normally engages a roller 25 which is mounted on the lower end of the tubular holder 12 of the movable electrode.

As thus described it will be appreciated that the device consists of few parts, and therefore it may be manufactured at a moderate cost. The spring is of such proportions that it normally 45 will move the electrode 11 to its lowermost position in the slotted sleeve 14 and will cause the plunger-bar to slide upwardly to its normal position shown in Fig. 1 of the drawing. However, this spring 16 is comparatively weak, and when the torch is placed on the cap 23 the weight of the torch will cause the plunger-bar to slide downwardly, and the electrode 11 will coincidentally slide upwardly.

In operation, when the torch 24' is placed upon 55

the cap 23 its inclined position will be in line with the arc formed by the electrodes, approximately parallel with the plates 6 and 7, said plates, together with the opening 5 in the top of the casing, forming a passageway for the flash which immediately occurs, and thereby tending to relieve other parts of the device from the effects of excessive heat. Since the electrodes are disposed in line vertically, the movable electrode will be lubricated automatically since the dust worn away from said electrodes by repeated ignitions will, in part, be deposited in the sleeve 14. Since the cap 23 is disposed at a suitable inclination it operates as a correct guide for the operator when handling the torch so that the gas therefrom will immediately become ignited and this feature proves to be of advantage to an operator since both hands are free for carrying on the work of welding.

20 I claim as my invention,—

1. An electrical torch ignition device comprising an upright rectangular casing having an opening in its top with parallel deflecting-plates extending inclinedly from opposed edges of said opening, and provided with a vertical, tubular guide, an energized, vertically disposed stationary electrode in the casing, a stationary, slotted sleeve in the casing, a second energized electrode, said second electrode being disposed in the vertical plane below the first named electrode and slidingly mounted in the sleeve, a rock-bar in the casing adjacent the second electrode, a plunger-bar in the tubular guide engaging the rock-bar and provided with a torch-supporting cap and adapted to be moved for moving the rock-bar to cause a movement of the second electrode toward the first named electrode.

2. An electrical torch ignition device comprising, in combination with an upright, rectangular casing having an opening in its top, a slotted sleeve in the casing secured to a wall thereof, a stationary energized electrode in the casing and extending into the slotted sleeve, a second energized electrode disposed in the slotted sleeve

with its longitudinal axis in line with the longitudinal axis of the first named electrode, a rock-bar movable for moving the second electrode toward the first named electrode, and a plunger-bar movable through the top of the casing for moving the rock-bar, said plunger-bar being provided with an inclined torch-holding cap extending in line with the electrodes and opening in the top of said casing.

3. In an electrical torch ignition device, a casing having an opening in its top and parallel deflecting plates at the edges of the opening extending inclinedly thereof, a stationary vertically disposed sleeve in the casing provided with a vertical slot, a stationary energized electrode extending into the sleeve, a second energized electrode, said second electrode being slidably mounted in the sleeve and disposed below the first named electrode, a rock-bar having an end-portion disposed below the second electrode, a plunger-bar extending through the top of the casing and engaging an end-portion of the rock-bar and adapted to be moved for actuating the rock-bar to cause the second electrode to move toward the first named electrode, said plunger-bar being provided with a cap of concave form for supporting a torch thereon and inclined toward said opening and said electrodes.

4. An electrical torch lighting device comprising a casing having an opening in its top with deflecting-plates to provide an inclined passageway into the casing, a slotted sleeve in the casing in line with the inclined passageway, an energized stationary vertically-disposed electrode in the sleeve, a slidably mounted energized electrode in the sleeve in line with the stationary electrode, a rock-bar movable for moving the slideable electrode toward the stationary electrode, and a plunger-bar movable into the casing for moving said rock-bar, said plunger-bar having an inclined torch-holding cap disposed in line with said passageway and said sleeve.

CLARENCE E. CADY.
